UNITED STATES PATENT OFFICE.

CHARLES ALGERNON PARSONS, OF NEWCASTLE-UPON-TYNE, AND STANLEY SMITH COOK, OF WALLSEND-UPON-TYNE, ENGLAND; SAID COOK ASSIGNOR TO SAID PARSONS.

SURFACE CONDENSER.

1,144,235.

Specification of Letters Patent. Patented June 22, 1915.

Application filed February 10, 1913. Serial No. 747,374.

To all whom it may concern:

Be it known that we, CHARLES ALGERNON PARSONS, K. C. B., a subject of the King of Great Britain and Ireland, and residing at 5 Heaton Works, Newcastle-upon-Tyne, in the county of Northumberland, England, and STANLEY SMITH COOK, a subject of the King of Great Britain and Ireland, and residing at Turbinia Works, Wallsend-upon-Tyne, in 10 the county of Northumberland, England, have invented certain new and useful Improvements in and Relating to Surface Condensers, of which the following is a specification.

15 This invention relates to improvements in surface condensers, viz., those in which the vapor to be condensed (which for convenience will hereinafter be referred to as steam) is caused to come into external contact with 20 a number of tubes through which a cooling medium is passed and relates more particularly to such condensers which have a cross-sectional area less in one dimension than in another perpendicular thereto, and in which 25 the natural direction of flow between the inlet and outlet, owing to their relative positions, is along a path of greater length than the shorter dimension of the condenser.

30 The conditions under which such condensers are employed often necessitate a large rate of condensation per square foot of the tube surface, particularly for instance when such condensers are used with the turbine installations for modern high speed 35 vessels on account of the large power adopted for such installations, and the limited space available for and consequently restricted size of the condenser. Under these 40 circumstances a considerable difference in pressure exists between the inlet to the condenser and the exhaust therefrom owing to the high velocity of the steam between the tubes, a condition which is inimical to good 45 vacuum being obtained at the exhaust end of the turbine.

The object of the present invention, therefore, is to enable such drop in pressure to be reduced as far as possible, and also to obtain a generally improved form of condenser.

The invention consists in a condenser having a cross sectional area less in one dimension than in another perpendicular

thereto, in which the steam or other vapor to be condensed is caused to flow at approximately all parts of the condenser in a direction substantially parallel to said shorter dimension independently of the shape of the condenser.

The invention also consists in the improved form of condenser hereinafter described.

Referring now to the accompanying drawings:—Figure 1 is a diagrammatic cross section of a vessel indicating the position of the condenser relative to the turbine and the framing of the vessel. Fig. 2 is a vertical cross section on the line Z Z of Fig. 3 through a condenser according to the present invention. Fig. 3 is a side elevation of 70 the condenser, shown in Figs. 1 to 2, viewed from the steam inlet side. Fig. 4, is a cross-sectional plan of Fig. 3, the sections on the left and right hand being taken on the planes Y Y and X X respectively. 75

As will be seen from Fig. 1, the position of the condenser, *a*, placed as it is between the turbine, *b*, and the framing, *c*, of the vessel requires that the condenser body shall be deep and narrow with the inlet, *d*, thereto in the upper part of the condenser, and the exhaust, *e*, therefrom arranged at the bottom. Under these conditions, the direction of flow of the steam owing to the relative positions of the inlet, *d*, and the exhaust, *e*, will be along the greatest dimension of the condenser, so that the steam has to traverse the spaces between the tubes at high velocity, and on this account and also because it has to traverse a great number of 85 rows of tubes a considerable difference in pressure exists between the inlet, *d*, and the exhaust, *e*, of the condenser, a condition which is inimical to good vacuum being obtained at the exhaust end of the turbine, *b*. 90 95

According to the present invention, the steam is caused to flow through such a condenser in such a manner that at approximately all parts of the condenser the flow is along substantially the shortest path 100 across the tubes.

In one way of carrying this invention into effect as shown in Fig. 2, a baffle, *f*, is arranged at the side of the condenser, *a*, opposite to that at which the steam enters by 105 the inlet, *d*. This baffle has perforations, *g*,

the area through which is small in relation to the area for the flow of steam between the tubes, h , by which means the steam is distributed evenly over such tubes. Behind this 5 perforated baffle, f , and the wall of the condenser, a , behind the same, a small space, j , is left, sufficient for the flow of mixed air and vapor which has to be drawn away by the exhaust means such as air pump, dry 10 air pump or vacuum augmenter connected to the exhaust, e , at the bottom of the condenser. A suitable space, k , is left between the first rows of the tubes, h , and the wall of the condenser, a , on the side at which the 15 inlet, d , is placed, in order that the steam may be distributed in a substantially even manner over the condenser surface through which it has to flow. The exhaust, e , may be separated from the tubes, h , by a solid 20 plate, m , so that the vapor to be withdrawn and the water of condensation must all pass through the perforated baffle, f , at the back of the tubes, h .

It is preferable that the first few rows of 25 the tubes, h , which the steam encounters be arranged as illustrated in a rectangular net work with the tube pitch transverse to the flow of steam greater than the tube pitch in the direction of the flow of steam, the re- 30 mainder of the tubes, h , being arranged in the usual equiangular pitching, or in any other convenient manner. By this means the distribution of the steam in an even man-

ner is further assisted, while the resistance to the flow of the steam is reduced. 35

Any other system of distribution of the tubes, h , may however be adopted.

Fig. 3, shows the general outline of the condenser shown in Figs. 1 and 2. The cooling water enters the header p , by the inlet n , 40 passes through the tube nest to the left hand header q , and escapes by the outlet o .

Having now described our invention what we claim as new and desire to secure by Letters Patent is:— 45

In combination in a surface condenser a casing, a tube nest within said casing, a free space within said casing on one side of said tube nest, a steam inlet opening into said free space, a second free space on the other side of said tube nest, a perforated baffle plate between said second free space and said tube nest, an outlet from said casing 50 communicating with said second free space the distance between said inlet and said outlet being greater than the distance between said free spaces through said tube nest and perforated baffle. 55

In testimony whereof, we affix our signatures in presence of two witnesses.

CHARLES ALGERNON PARSONS.
STANLEY SMITH COOK.
